GLASS CUTTER

William Bierman, New York, N. Y.

Application May 16, 1940, Serial No. 335,469

6 Claims. (Cl. 49—48)

This invention relates generally to glass cutting devices. More particularly, my invention is directed to an improved glass cutting device adapted for opening filled ampoules or for cutting any other type of glass tubing.

One of the objects of my invention is to provide a glass cutting device of the character described which shall be so designed that the probabilities of splintering or breaking of the glass during the cutting process will be reduced to a minimum.

Another object of my invention is to provide a glass cutting device of the character described which shall be provided with an improved cutting member, so constructed and arranged as to be unaffected by the variations from the normal in the outer surface of the ampoule or glass tube to be cut.

Still another object of my invention is to provide a glass cutting device for opening filled ampoules or for cutting glass tubing provided with novel means for accurately cutting such tubing to required lengths, and which at the same time shall be characterized by its simplicity of construction and its high degree of efficiency in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing, in which is shown one of the various possible embodiments of this invention,

Fig. 1 is a longitudinal sectional view of a glass cutting device constructed in accordance with my invention;

Fig. 2 is an end elevational view thereof, partly in section;

Fig. 3 is a front elevational view, partly sectional, of a modified form of my invention;

Fig. 4 is a cross sectional view taken substantially on the line 4—4 of Fig. 3;

Fig. 5 is an enlarged cross sectional view taken substantially on the line 5—5 of Fig. 3; and

Fig. 6 is an enlarged sectional detail of a modified form of my invention relating to the mounting for the abrasive element.

Referring now in detail to Figs. 1 and 2 of the drawing, there is described a type of glass cutting device 10 constructed in accordance with my invention and adapted for opening filled ampoules or for cutting glass tubing. The device 10 may be made compact so that it may be con-

veniently carried in a vest pocket of the physician or other user thereof, and comprises a relatively flat disc member 11. The said disc 11 is made of rigid material and is preferably provided with a 5 triangularly shaped central axial aperture 12 adapted to receive therein a section of glass tubing 13 or the tubular end of an ampoule which it is desired to cut. The disc 11 is also provided with a threaded opening 14 having its axis disposed at right angles to the axis of the aperture 12 and communicating therewith.

In the opening 14 there is mounted a cutting element comprising the following construction. A tubular housing member 15 is provided with an externally threaded shank portion 15a which is 20 threadedly received in the threaded opening 14 to hold the same in rigid attachment to the disc 11. Axially slidably mounted within the housing 15 is a tubular plunger member 16 which is adapted to project into the aperture 12 through the inner open end of the housing 15. The opposite end of the housing 15 may be closed off by a threadedly attached knurled cap 17. Fixedly attached to that end of the plunger 16 which projects into the aperture 12 is a glass scoring or cutting member 20 which may take the form of a diamond or other suitable abrasive member. The member 20 may be mounted directly on the plunger 16 or it may be mounted on an independent 25 plug member 21 threadedly received in the said plunger 16 so as to be more readily removed for repair or replacement. A spring 22 within the plunger 16, having opposite ends thereof pressing against the cap 17 and plug 21, serves to normally 30 resiliently urge the diamond 20 in a direction toward the glass tube 13 within the aperture 12. An outwardly extending flange 16a on the plunger 16 cooperating with the shoulder 15b of the housing 15 limits the movement of the plunger 16 in 35 a direction toward the aperture 12.

It is thus seen from the above described construction that when it is desired to open an ampoule or to cut a glass tube it is merely necessary to place the same in the aperture 12 in any selected position. The plunger 16, being spring 45 pressed, will cause the diamond 20 to resiliently press against the outer surface of the glass tube. If the disc is then axially rotated while the glass tube is held stationary or vice versa the diamond 20 will score a circumferential line at the point 50 which it is desired to cut the tube. The glass tube is then removed from the aperture 12 and pressure applied on either side of the scored circumferential line to break the tube at such line 55 with a clean break, leaving no splinters or rough

edges. Should the external surface of the tube 13 possess irregularities, such as depressions or projections at the point of scoring the spring 22 will cause the diamond 20 to accommodate itself to such irregularities and thus prevent breakage of the tube 13.

In Figs. 3, 4 and 5 I have shown a modified form of my invention in which the apparatus is adapted to be fixed in position on a table surface and which is particularly suited for the cutting of measured lengths of glass tubing.

In this form of my invention, instead of the disc 11, the threaded housing shank 15 is fixedly received in a correspondingly threaded opening 38 of a flange 31 integral with a frame 32. The frame 32 is rotatably mounted on a sleeve 33 by means of any suitable type of annular ball or roller bearing construction, such for example as the ball bearing unit 35, as shown in Fig. 3. The sleeve 33 is provided with a reduced diameter portion 33a which is frictionally received in a split bearing portion 36, 36' of a support 37 which is adapted to be fixedly attached to a table surface 38 by means of the screws 39. The collar 33 is provided with a triangular shaped axial opening 40, similar in shape and function to that of the aperture 12 in the disc 11. An opening 41 is provided in the frame 32, in axial alignment with the sleeve opening 40, so that a glass tube 50 which it is desired to cut may be inserted in the opening 40 of the collar 33 and project beyond the frame 32 to be in position for circumferential scoring by the spring pressed cutting element 20.

As shown in Figs. 3 and 5, a portion of the wall 33b of the sleeve 33 is cut away for the convenience of insertion of the tube 50. In operating the Figs. 3 to 5 form of my invention, the tube 50 is positioned in the sleeve 33 as shown in Fig. 3, and while the tube 50 is held fixed in position with one hand the frame 32 is rotated with the other hand thus causing the diamond 20 mounted thereon to score a circumferential groove in the outer surface of the tube 50 at the point which it is desired to cut the said tube, after which the tube 50 is severed at the scoring point in the manner hereinbefore described.

In order to be able to accurately cut desired lengths of glass tubing, I have provided the following gauging mechanism for use in conjunction with the apparatus shown in Fig. 3.

Integral with the support 37 is a longitudinal tubular member 43, parallel to the collar 33 and provided with a non-circular axial opening 44 into which there is slidably mounted a scale member 45 of corresponding cross-sectional contour. The scale member is suitably marked to measure length and is provided at one end thereof with a portion 46 disposed at an angle to the longitudinal axis of the scale and so arranged as to have the upper end thereof disposed in the path of sliding movement of the said tube 50. One end 43a of the tubular member 43 terminates in exact alignment with the diamond 20, so that the distance from the inner surface 46a of the arm 46 to the point of the diamond 20 will equal the distance from the said arm surface 46a to the extreme edge of the portion 43a of the member 43. It is therefore seen that if it is desired to cut a glass tube length of one inch, it is merely necessary to first slidably move the gauge 45 until the numeral one is exactly aligned with the edge of the member portion 43 (see Fig. 3) and then slidably move the tube 50 until the end thereof abuts the arm 46. A set screw 52 is pro-

vided to frictionally lock the scale 45 in any selected position.

In Fig. 6 of the drawing, I have illustrated in detail a modified form of my invention relating to the mounting of the abrasive element so that the same may be more readily removed and replaced without disassembling the device. In this form of my invention the end of the plunger member 60 is provided with an internally threaded portion 61. Into this threaded portion 61 is threadedly mounted a plug member 62. The plug member 62 is provided with an axial opening 63 adapted to receive therethrough and to project outwardly beyond the plug 62, an abrasive member 64 made of any suitable material which will satisfactorily provide a circumferential score on the glass tube to be cut. The abrasive member 64 is provided with an outwardly extending flange 65, larger than the opening 63 and interposed between the plug 62 and the plunger 60, which holds the said abrasive member 64 captive. The same type of spring 22 is employed within the plunger 60.

It is thus seen that when the tip of the abrasive member 64 becomes dulled, it is merely necessary to unscrew the plug 62 and to readily remove and replace the abrasive member 64.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim 40 as new and desire to secure by Letters Patent:

1. In a glass tube cutting device of the character described, the combination of a plunger member, a housing for said plunger member, an abrasive member provided with an outwardly extending flange, means for removably mounting said abrasive member on said plunger member for movement therewith, said last named means comprising a plug member provided with an opening and removably attached to said plunger member, said abrasive member being received within said opening and projecting therethrough and said flange overlying the inner end of said plug member to hold the said abrasive member captively in place, means for supporting said glass tube, and means for normally resiliently urging said plunger member in a direction toward said glass tube so as to cause the abrasive member to contactively engage the outer surface of said glass tube.

2. In a glass tube cutting device of the character described, means for supporting a glass tube, a housing adjustably mounted relative to said support for movement to and away from said tube, a plunger slidably mounted in said housing, resilient means associated with said plunger and said housing and bodily movable with said housing to resiliently urge said plunger toward said glass tube, manually manipulatable means carried by said housing to vary the position of said housing relative to said tube and to vary the pressure of said resilient means, and an abrasive member carried by said plunger.

3. In a glass tube cutting device of the character described, means for supporting a glass tube, a housing adjustably mounted relative to

said support for movement to and away from said tube, a plunger slidably mounted in said housing, resilient means associated with said plunger and said housing and bodily movable with said housing to resiliently urge said plunger toward said glass tube, a single manually manipulatable member carried by said housing to vary the position of said housing relative to said tube and to vary the resilient pressure of said resilient means, and an abrasive member carried by said plunger.

4. In a glass tube cutting device of the character described, means for supporting a glass tube, an open-ended exteriorly threaded housing threadably mounted in said support for movement to and away from said glass tube, a plunger slidably mounted in said housing for movement to and away from said glass tube, one end of said plunger projecting through an open end of said housing, the other end of said housing being closed by a cap threadably received thereon, a spring compressed between said cap and said plunger whereby to urge said plunger resiliently toward said glass tube, and an abrasive member carried at the end of said plunger adjacent said glass tube.

5. In a glass tube cutting device of the character described, means to support a glass tube, said means comprising a disc having an axial opening therein, two of the walls of said opening converging, a third wall of said opening being opposed to the point of convergence of said first two walls, an elongated housing supported in the

portion of said disc adjacent said third wall, said housing projecting into said opening and being longitudinally directed toward said point of convergence, means for adjustably mounting said housing in said disc for movement toward and away from said point of convergence, and an abrasive member supported at the end of said housing in said opening.

6. In a glass tube cutting device of the character described, means for supporting a glass tube, said means comprising a disc having an axial opening therein, two of the walls of said opening converging, a third wall of said opening being opposed to the point of convergence of said first two walls, an open-ended exteriorly threaded elongated housing threadably mounted in the portion of said disc adjacent said third wall for movement to and away from said glass tube, said housing projecting into said disc opening and being longitudinally directed toward said point of convergence, a plunger slidably mounted in said housing for movement to and away from said glass tube, one end of said plunger projecting through the open end of said housing disposed in said disc opening, the other end of said housing being closed by a cap threadably received thereon, a spring compressed between said cap and said plunger whereby to urge said plunger resiliently toward said glass tube, and an abrasive member supported on the end of said plunger adjacent said glass tube.

WILLIAM BIERMAN.
